(57) **CLAIM**

The ornamental design for a bottle, as shown and described.

DESCRIPTION

FIG. 1 is a perspective view of a bottle showing my new design;

FIG. 2 is front elevational view of the bottle of FIG. 1; FIG. 3 is a rear elevational view of the bottle of FIG. 1; FIG. 4 is a right side elevational view of the bottle of FIG. 1;

FIG. 5 is a left side elevational view of the bottle of FIG. 1; FIG. 6 is a top plan view of the bottle of FIG. 1; FIG. 7 is bottom view of the bottle of FIG. 1;

FIG. 8 is a perspective view of another embodiment of the bottle of the new design;

FIG. 9 is front elevational view of the bottle of FIG. 8; FIG. 10 is a rear elevational view of the bottle of FIG. 8;

FIG. 11 is a right side elevational view of the bottle of FIG. 8;

FIG. 12 is a left side elevational view of the bottle of FIG. 8;

FIG. 13 is a top plan view of the bottle of FIG. 8; and, FIG. 14 is bottom view of the bottle of FIG. 8.

The broken lines shown in the Figures represent portions of the bottle that form no part of the claimed design.
